UNITED STATES PATENT OFFICE

WILLIAM STAHLY, OF COLLEGE POINT, NEW YORK, ASSIGNOR TO SANITARY PUBLIC SERVICE CORPORATION, OF NEW YORK, N. Y., A CORPORATION OF NEW JERSEY

MACHINE FOR MAKING AND VENDING OR DISPENSING TOILET SEAT COVERS AND THE LIKE

Application filed December 11, 1929. Serial No. 413,186.

The present invention relates to machines for making and vending or dispensing toilet seat covers and the like.

The present invention contemplates an improved machine for this purpose wherein all the parts are designed and arranged for easy assembly in a small cabinet adapted to hold a supply of tissue in the form of a roll, and to form and dispense the toilet seat covers ready for use. The seat cover, or other paper articles such as a towel, is formed out of the web by cooperative male and female rolls bearing a predetermined design. These rolls are preferably arranged for tearing the paper along the desired lines instead of cutting it by a sharp knife.

An object of the present invention is to provide a machine for this purpose wherein the moving parts are all carried on two frame members which can be assembled into a cabinet, the cabinet forming the support for the frame members and holding the parts in position.

The invention relates to a machine for forming articles from the entire width of a web of paper and dispensing the same, the articles being formed having severed ends oblique to the edge of the web, the machine being so designed that the web of paper passes between male and female rolls which are out of contact except for the cooperative knives and grooves provided to sever the paper, the tension necessary for drawing the paper between these rolls being provided by a driven pressure roller which is spaced sufficiently close to the plane of severing of the male and female rolls to engage with the advancing edge of the web before the preceding article has been completely severed. In this way a pulling effort is always applied to the web to draw it between the male and female rolls even though they are out of contact.

A further object of the invention is to provide a paper straightening device such as a spiral roller for stretching or straightening the paper so as to prevent the formation of longitudinal creases as it passes through the machine.

A further object of the invention is to provide guiding and pressure rollers for holding

the paper on the female roll, both these rollers being spring-pressed toward the female roll, the pressure roller being preferably gear-driven.

A further object of the invention is to provide an improved arrangement for supporting the paper roll while the paper is being threaded into the machine.

A further object of the invention is to provide an improved means for stopping the seat-forming mechanism at the end of a cycle, and to provide coin control mechanism.

Other and further objects of the invention will appear as the description proceeds.

The accompanying drawings show, for purposes of illustrating the present invention, one of the many embodiments in which it may take form, it being understood that the drawings are illustrative of the invention rather than limiting the same.

In these drawings:

Figure 1 is a front elevational view of the seat cover forming machine with parts broken away to show the interior construction, the parts being in the position to which they are brought at the end of a seat cover forming operation;

Figure 2 is a horizontal sectional view taken on the line 2—2 of Figs. 1 and 4;

Figure 3 is a perspective view of the male cutting roller;

Figure 4 is a vertical sectional view on the line 4—4 of Fig. 1;

Figure 5 is a sectional view on the line 5—5 of Fig. 1 and showing in dot and dash lines the position of the cover before it is closed and the position of the release mechanism after the insertion of a coin in the coin-control mechanism;

Figure 6 is a fragmentary view on an enlarged scale showing the stop and release mechanism; and

Figure 7 shows a seat cover formed in the present machine, and illustrates diagrammatically the respective relative positions of the lines of contact of the pressure roll and female roll and the meeting point or plane of the knives and grooves of the male and female rolls.

The present machine is shown as being em-

bodied in a sheet metal cabinet adapted to be mounted on the wall or other convenient support. The cabinet is open at the front and has a back wall 10, side walls 11 and 12 and a two-part bottom wall 13, 14. The front edge of the lower bottom wall part 13 is bent upwardly and rearwardly, as indicated at 15, while the rear edge of the front part 14 of the bottom wall is bent upwardly as indicated 10 at 16. The parts 15 and 16 form a delivery chute for the formed seat cover.

The front cover of the cabinet is shown at 17. It is hinged as indicated at 18 and at the top extends rearwardly as indicated at 15 19 to close the top of the cabinet. It is adapted to be locked in this position by a key controlled lock indicated at 20. The cover also has side walls 21 and 22 extending rearwardly and adapted to overlie the side walls 11 and 12 20 of the stationary part of the cabinet.

As here shown, the seat-forming mechanism is carried between two plates 23 and 24. These plates are secured to the side walls 11 and 12 of the cabinet by screws, indicated at 25 25, these screws passing through holes in the side walls of the cabinet, and being threaded into tapped holes in the cast frame plates 23 and 24. The male roller 26 for the seat cover forming mechanism is shown more in detail 30 in Fig. 3. It may be carried on a shaft 27 mounted in bearing holes 28 in the frame plates 23 and 24. This shaft carries three discs 28', 29 and 30 and these discs carry the male cutting or tearing knives for forming 35 the seat cover.

The machine herein shown is arranged to form a seat cover of the shape shown in Fig. 7. The front end of the seat cover is the first to emerge from the machine and is V-shaped 40 as indicated at *a*, *a'*. The rear end of the seat cover is also V-shaped as indicated at *b*, *b'*. An oval flap is cut centrally in the cover, the flap having the shape indicated at *c*.

15 The male roll is provided with two dull knives indicated at 31 and 32. The knife 31 is in the form of a strip of sheet metal, as appears more clearly in Fig. 3, and is secured to the three discs 28', 29 and 30 by screws indicated at 33. This knife is provided with 50 spiral edges 34 and 35 arranged normal to the surface of the cylinder, these edges 34 and 35 being formed by bending the sheet metal outwardly. They are adapted to form 55 the V-shaped ends *a*, *a'*, *b*, *b'* of a seat cover.

The helical shape of the severing device makes it easy to sever the paper in a hand-operated machine. The knives 33 and 34, as here shown, are separated at 36, this narrow 60 gap being provided so that the seat cover formed is not completely severed from the material remaining in the machine. The flap forming knife 32 is also made of sheet metal.

It is provided with continuously curving 65 edges 37 arranged normal to the surface of

of the cylinder, and of such shape as to cut the flap *c*. The cutter 32 is secured to the disc 29 by screws 38. This male roll forms the subject matter of divisional application Ser. No. 502,905, filed December 17, 1930.

70 The female roll is indicated at 40. It is one-half the diameter of the male roll and is provided with a curved slot 42 adapted to receive the cutting edges 37 of the flap forming knife, and with other helical slots 43 adapted to receive the end forming knives 34 and 35. This female roll may be made out of any suitable material, such for example as a molded material. It is mounted on a length 80 of tubing 45 which carries spur gears 46 and 47.

The gears 46 and 47 are mounted on a shaft indicated at 48, this shaft being carried in the frame plates 23 and 24. The gear 46 on the right-hand end of the roll 40 meshes with a gear 48 carried on the shaft 27 of the male roller. This gear is twice the size of the gear 46 so as to maintain a two-to-one relation between the male and female rolls.

85 A guide roll 50 is carried in elongated bearing openings 51 at the front of the frame plates 23 and 24. This guide roll is preferably provided with a double spiral rubber paper spreading device 52, and is held against the surface of the female roller so as to press the paper against the female roller and spread the paper away from the center to prevent the formation of longitudinal creases.

90 A pressure roll 53 is provided to draw the 100 paper through the machine in a manner to be described below. It is mounted to the rear of the female roller, being preferably carried in elongated slots 54 in the plates 23 and 24, and driven by a gear 55 meshing 105 with the gear 47. This pressure roller may, if desired, be made in the form of a shaft or rod 56 and provided with spaced rubber squeeze rollers 57. The rolls 50 and 53 are held against the surface of the female roller 110 by coiled springs 58 carried between the gears and end plates. During the formation of the flap in the seat cover narrowing of the web is prevented by the pressure roll 53 which engages the entire width of the web of paper. This roll also grips the entire 115 width of the seat cover after severing and holds it while it hangs from the machine and until it is torn away. The shaft 48 is driven by a crank C, and forward turning of the parts is insured by a pawl 59.

120 The cover 17 is provided with angle members 60 and 61 adapted to support the ends of a shaft 63. This shaft carries a roll of tissue 64 from which the toilet seat covers are to be made. In inserting the paper into the machine, the cover is lowered about the hinge 18 and allowed to hang down, the roll 125 of paper placed in position with the shaft 63 underneath the flanges 60 and 61. The 130

end of the paper is then passed underneath the guide roll 50 and between the male and female rollers, these rollers being actuated by the crank C. After the paper passes between the rolls 26 and 40, the paper is guided downwardly by the pressure roll 53 and passes out through the chute as will be clear from Figs. 4 and 5. The cover 17 may then be raised up to close the cabinet. This carries the roll up to the position indicated in full lines in Figs. 4 and 5 without disturbing the paper which has been previously fed through between the rolls. The paper rides against springs 64a and 64b carried in the inside of the cover. These springs keep the paper away from the front of the box and produce a friction drag against the paper sufficient to keep it taut during severing and prevent overrun when the machine is stopped at the end of the seat cover forming operation.

It will be noted that the female roll is smooth, except for the grooves or slots 42 and 43 which receive the edges 37 of the flap forming knife and the edges 34 and 35 of the end forming knives, and that these edges project outwardly from supporting parts which are well within the pitch circle of the gear 48 and hence that there is no rolling contact of the male and female rolls whereby the paper may be drawn off the supply roll against the friction drag set up between the paper roll and the stationary members 64a and 64b. Owing to the absence of rolling contact between the male and female rolls ordinarily employed in paper handling machinery, it is necessary to arrange other means for imposing a pull on the paper at all times when withdrawal of the paper is to be accomplished.

Figure 7 shows in full lines the edges of a web of paper, a completely formed seat cover, (suspended), and the initial cut made for forming the flap of the next succeeding seat cover. The heavy lines CP and PP indicate the cut-off plane and pressure plane, respectively, at the end of the cycle, and their spacing indicates the arc between these planes, measured on the surface of the female roll. The dotted lines cp and pp at the top of the figure, together with the dotted representation of a seat cover, show these planes just before the completion of the formation of the seat cover. The oblique lines for the ends of the seat cover intersect the lines cp and pp and hence a portion of the web, still connected with the supply roll, is carried beyond the cutting plane and under the pressure roll so as to be available for pulling the paper off the supply roll. It is thus important that the angle on the female roll occupied by the cut-off grooves should exceed the angular spacing of the planes of severing and pressure application.

In order that the machine may make a single seat cover and then automatically stop, it is provided with an automatic stop mechanism indicated at 65 which functions to stop the machine when a seat cover has been completed and is in position to be taken from the machine. When the machine is designed for dispensing toilet seat covers, this release mechanism 65 may be manually actuated to release the seat-forming mechanism and automatically actuated to stop the machine. In the present case, however, the machine shown is designed for vending, and the release of the automatic stop 65 is by a coin control mechanism to be described.

A coin may be inserted through a hole 70 in the upper front part of the cover and passes downwardly and rearwardly in a chute 71 carried by the hinged cover 17. This chute delivers the coin into a vertical chute 72 secured to the rear wall of the cabinet 10 by bolts indicated at 73. This coin chute may be formed of sheet metal and is arranged to allow the coin to drop into the bottom of the cabinet. As the coin passes downwardly through the chute, it strikes a rear finger 74 forming part of a bifurcated spring pressed trigger member 75.

This trigger member is pivoted at 76 on the coin chute 72 and the upper end is urged forwardly by a leaf spring 77. The front bifurcation of the trigger member is indicated at 78. It is provided with a shoulder or notch 79 adapted to receive a rearwardly extending arm 80 of the stop mechanism. The passing of the coin past the trigger mechanism swings the trigger clock-wise as viewed in Fig. 4 and releases a spring-pressed member 80 from the notch 79 causing it to swing in a clock-wise direction under the influence of a leaf spring 81. This moves the top of the arm 80 down past the lower edge or cam surface 82 of the bifurcation 78, and at the same time operates to release the seat-forming mechanism 65.

The arm 80 is carried by a mutilated shaft 83 mounted in the end plate 24. This shaft is cut away as indicated at 84 in Fig. 6. When the stop mechanism is in position to stop the seat-forming mechanism, the mutilated shaft 83 is in such a position that the upper front corner 85 of the same will engage with a pin 86 carried by the gear wheel 48 to thereby arrest the seat-forming mechanism. When, however, the trigger mechanism 74 is actuated by the coin, the spring 81 acts to shift the mutilated shaft from the full line position, Fig. 6, to the dotted line position. This moves the upper shoulder 85 far enough in a counter-clock-wise direction, as appears in Fig. 6, to permit the pin 86 to pass by. This pin then passes beyond the mutilated shaft and engages with a resetting cam 87 carried thereby so that the mutilated shaft and arm 80 are moved back up so as to

reset the trigger mechanism. The seat-forming mechanism is then carried through the cycle and is stopped at the proper time.

The coins accumulate behind the wall 15 and on top of a closure device 88 hinged at 89 and locked by a lock 90.

When one desires to test the seat-forming mechanism without employing a coin, a small instrument may be passed into the coin controlled mechanism to press back the upper end 75 of the trigger.

At the end of the seat cover forming operation, the paper has been carried forward until the line $p' p'$ indicates the approximate position of the line of pressure on the next partially formed seat cover. The newly formed seat cover hangs downwardly as indicated in Fig. 1, being supported at the center by the unsevered paper. One can then 20 grasp the seat cover at the point marked "X", Fig. 7, and gently pull it away from the machine.

The machine may readily be adapted for dispensing other paper articles, such as paper towels, by omitting the flap forming knives on the male roll.

In order that the coin controlled mechanism may be rendered inoperative after the paper supply has been exhausted, the machine is provided with a pivoted link 91 having its lower end behind a spring 92 which bears against the end of the shaft 63 carrying the paper supply. So long as there is sufficient paper in the machine, the lever 91 will be in the position indicated in Fig. 1, and the slot 70 will be open for the reception of a coin. When, however, the paper supply is depleted sufficiently to have the end of the shaft 63 pass beyond the lower end of the spring 92, this spring will actuate the lever 91 to close the coin chute. An inspection opening 93 permits one to determine the amount of paper remaining in the roll.

This application is a continuation in part 45 of my application Serial No. 356,825, filed April 20, 1929.

It is obvious that the invention may be embodied in many forms and constructions within the scope of the claims, and I wish it 50 to be understood that the particular form shown is but one of the many forms. Various modifications and changes being possible, I do not otherwise limit myself in any way with respect thereto.

55 I claim:

1. A machine for forming toilet seat covers out of a web of paper and dispensing the same, comprising, means for supporting a roll of paper, male and female rolls meshing 60 together and having a predetermined design to form the seat cover, a revolvable guiding roll for applying the paper to the female roll in advance of the meeting point of the male and female rolls, a pressure roll on the 65 other side of the meeting plane for pressing

the paper against the female roll, and gear means for driving the pressure roll.

2. A machine for severing a web of paper to form paper articles and dispense the same, comprising, means for supporting a roll of paper, male and female rolls, meshing together and having severing devices to cut the articles from the web, a revolvable guiding roll for applying the paper to the female roll in advance of the meeting point of the male and female rolls, a pressure roll on the other side of the meeting plane for pressing the paper against the female roll, and gear means for driving the pressure roll, loose 70 bearings for the pressure roll, and spring means for holding the pressure roll against the female roll.

3. A machine for severing a web of paper to form paper articles and dispense the same, comprising, means for supporting a roll of paper, male and female rolls meshing together and having severing devices to cut the articles from the web, a revolvable guiding roll for applying the paper to the female roll in advance of the meeting point of the male and female rolls, a pressure roll on the other side of the meeting plane for pressing the paper against the female roll, and gear means for driving the pressure roll, loose 75 bearings for the pressure roll, and spring means for holding the pressure roll against the female roll.

4. A machine for severing a web of paper to form paper articles and dispense the same, comprising, means for supporting a roll of paper, male and female rolls meshing together and having severing devices to cut the articles from the web, a revolvable guiding roll for applying the paper to the female roll in advance of the meeting point of the male and female rolls, a pressure roll on the other side of the meeting plane for pressing the paper against the female roll, gear means 80 for driving the pressure roll, end plates in which all said rolls are revolvably mounted, the journals for the pressure roll being elongated in a direction radial of the female roll, and springs for pressing the pressure roll against the female roll.

5. A machine for severing a web of paper to form paper articles and dispense the same, comprising, means for supporting a roll of paper, male and female rolls meshing together and having severing devices to cut the articles from the web, a revolvable guiding roll for applying the paper to the female roll in advance of the meeting point of the male and female rolls, a pressure roll on the other side of the meeting plane for pressing the paper against the female roll, gear means for driving the pressure roll, end plates in which all said rolls are revolvably mounted, the journals for the pressure roll and guiding roll being elongated in directions radial 105 of the female roll.

- of the female roll, and springs connecting the rolls for pressing both of them against the female roll.
6. In a machine for severing a web of paper to form paper articles, male and female rolls meshing together and having severing devices to cut the articles from the web, shafts on which the rolls are mounted, a revolvable guiding roll for applying paper to the female roll in advance of the meeting point of the male and female rolls, a pair of plates each having bearings for all said rolls, and an inclosing housing having end walls to which the plates are secured.
- 15 7. In a machine for severing a web of paper to form paper articles, male and female rolls meshing together and having severing devices to cut the articles from the web, shafts on which the rolls are mounted, a revolvable guiding roll for applying paper to the female roll in advance of the meeting plane of the male and female rolls, a pressure roll on the other side of the meeting point for pressing the paper against the female roll, gear means for driving the pressure roll, a pair of plates having fixed bearings for the male and female rolls and slots to receive the shafts of the guiding and pressure rolls, springs interconnecting the guiding and pressure rolls to hold them against the female roll, and an inclosed housing having end walls to which the plates are secured.
- 20 8. In a machine for severing a web of paper to form paper articles, male and female rolls meshing together and having severing devices to cut the articles from the web, the male roll being twice the diameter of the female roll, a paper supply roll supported above the male roll and adapted to deliver a web of paper downwardly, a male guide roll for applying the paper to the female roll before it passes between the rolls, a pressure roll to press the paper against the female roll after it has passed between the rolls, and gear means for driving the pressure roll.
- 25 9. In a machine for severing a web of paper to form paper articles, a cabinet having an open front, a cover hinged to the lower front part of the cabinet and adapted to hang downwardly or to be raised up to close the cabinet, male and female rolls rotatably carried in the cabinet, the rolls meshing together and having severing devices to cut the articles from the web, the male roll being above the female roll, rolls for applying the paper to the female roll, and cover carried means for supporting a supply roll of paper when the cover is lowered or when the cover is raised.
- 40 10. In a machine for severing a web of paper to form paper articles, a cabinet having an open front, a cover hinged to the lower front part of the cabinet and adapted to hang downwardly or to be raised up to close the cabinet, male and female rolls rotatably carried in the cabinet, the rolls meshing together and having severing devices to cut the articles from the web, the male roll being above the female roll, rolls for applying the paper to the female roll, and cover carried means for supporting a supply roll of paper when the cover is lowered or when the cover is raised.
- 45 11. In a machine for severing a web of paper to form paper articles, male and female rolls meshing together and having severing devices to cut the articles from the web, the male roll being above the female roll, rolls for applying the paper to the female roll, and cover carried means for supporting a supply roll of paper when the cover is lowered or when the cover is raised.
- 50 12. In a machine for severing a web of paper to form paper articles, male and female rolls meshing together and having severing devices to cut the articles from the web, the male roll being above the female roll, rolls for applying the paper to the female roll, and cover carried means for supporting a supply roll of paper when the cover is lowered or when the cover is raised.
- 55 13. In a machine for severing a web of paper to form paper articles, male and female rolls meshing together and having severing devices to cut the articles from the web, the male roll being above the female roll, rolls for applying the paper to the female roll, and cover carried means for supporting a supply roll of paper when the cover is lowered or when the cover is raised.
- 60 14. In a machine for severing a web of paper to form paper articles, male and female rolls meshing together and having severing devices to cut the articles from the web, the male roll being above the female roll, rolls for applying the paper to the female roll, and cover carried means for supporting a supply roll of paper when the cover is lowered or when the cover is raised.
- 65 15. In a machine for severing a web of paper to form paper articles, male and female rolls meshing together and having severing devices to cut the articles from the web, the male roll being above the female roll, rolls for applying the paper to the female roll, and cover carried means for supporting a supply roll of paper when the cover is lowered or when the cover is raised.

gether and having severing devices to cut the articles from the web, the male roll being above the female roll, rolls for applying the paper to the female roll, and devices carried by the sides of the cover for supporting a supply roll of paper when the cover is raised, the top of the cover supporting the roll when the cover is lowered.

16. In a machine for forming toilet seat covers out of a web of paper, male and female rolls meshing together and having a predetermined design to form a seat cover with a central flap and incompletely sever the seat covers from one another, and a pressure roll for pressing the web of paper against the female roll and disposed to grip the entire width of the web of paper after severing to thereby hold the formed but incompletely severed seat cover suspended.

17. In a machine for forming toilet seat covers out of a web of paper, male and female rolls meshing together and having a predetermined design to form a seat cover with a central flap, a guide roll for applying the paper to the female roll, and a pressure roll for pressing the web of paper against the female roll, the severing of the flap taking place between the guide roll and the pressure roll, the pressure roll engaging the entire width of the paper during the cutting of the central flap to prevent narrowing the web as said flap is cut.

18. A machine for severing a web of paper to form paper articles and dispense the same, comprising means for supporting a roll of paper, male and female rolls meshing together and having severing devices to cut the articles from the web, a revolvable guiding roll for applying the paper web to the female roll in advance of the meeting point of the male and female rolls, a pressure roll on the other side of the meeting point for pressing the paper against the female roll, and gear means for driving the pressure roll.

19. In a machine for severing a web of paper to form paper articles, male and female rolls meshing together and having severing devices which cut the web to form the articles to shape without completely severing the same, and a pressure roll for pressing the web of paper against the female roll and disposed to grip the entire width of the web of paper after severing to thereby hold the formed but incompletely severed article suspended.

20. A machine for severing a web of paper to form paper articles and dispense the same, comprising means for supporting a roll of paper, a cylindrical female roll having grooves, a male roll having knives with paper severing edges which enter the grooves, the male roll being otherwise out of rolling contact with the female roll, gear means for driving the rolls so that the knife edges enter the grooves to sever the web into articles, a

revolvable guiding roll for applying the paper web to the female roll in advance of the meeting point of the male and female rolls, a pressure roll on the other side of the meeting point for pressing the paper against the female roll, and gear means for driving the pressure roll, the pressure roll acting to impose tension on the paper and draw it between the male and female rolls.

- 10 16. A machine for severing a web of paper to form paper articles and dispense the same, comprising means for supporting a roll of paper, male and female rolls meshing together and having cooperative severing devices shaped to provide paper articles with V-shaped ends, a revolvable guiding roll for applying the paper to the female roll in advance of the meeting point of the male and female rolls, a pressure roll on the other side 20 of the meeting point for pressing the paper against the female roll, and gear means for driving the pressure roll and disposed close enough to the meeting point to grip the web before the preceding article has been completely formed whereby the pressure roll acts as a drawing roll to pull the paper web.

17. In a paper handling machine, means for supporting a supply roll of paper, a friction device to resist removal of the paper 30 from the roll, two rolls between which the paper is passed, one being a pressure roll to press the paper against the other so that rotation of said rolls effects a removal of paper from the supply roll, the other roll having 35 end forming grooves extending across the face thereof and over which the paper is drawn and held taut, a rotary cut off knife which passes through the paper thus held taut and enters the grooves, and gears for 40 driving the two rolls and the knife, the grooves extending about the surface of the roll an angular distance at least as much as the angular spacing of the pressure roll and cut off knife about the axis of the grooved 45 roll.

18. In a paper handling machine, means for supporting a roll of paper, means for severing the entire width of a paper web to form articles of paper comprising a grooved female roll, a male cut off knife, means to revolve the roll and knife at the same peripheral speed so that the knife may enter the groove, means to deposit the web of paper about the surface of the grooved roll and hold it there so that the knife may sever it, said means comprising a pressure roll pressing the paper against the grooved roll to draw the paper off the supply roll, and a friction device to resist such withdrawal and hold 55 the paper taut against the female roll.

Signed at College Point in the county of Queens and State of New York, this 6th day of December, 1929.

WILLIAM STAHLY.
